(57) **CLAIM**

The ornamental design for a housing of a computing device, as shown and described.

DESCRIPTION

FIG. 1 is a bottom plan view of the housing of a computing device showing our new design;

FIG. 2 is a top plan view thereof;

FIG. 3 is a side view thereof;

FIG. 4 is an opposite side view thereof;

FIG. 5 is a back view thereof;

FIG. 6 is a front view thereof;

FIG. 7 is a bottom perspective view thereof; and,

FIG. 8 is a top perspective view thereof.

Broken lines shown in the drawings illustrate portions of the housing of a computing device, and form no part of the claimed design.
